(57) **CLAIM**

The ornamental design for an auxiliary monitor system, as shown and described.

DESCRIPTION

FIG. 1 is a front view of an auxiliary monitor system design in a closed configuration;

FIG. 2 is a right side view thereof;

FIG. 3 is a top front right perspective view thereof;

FIG. 4 is a top plan view thereof;

FIG. 5 is a bottom plan view thereof;

FIG. 6 is a front view of the auxiliary monitor system design of FIG. 1 in an open configuration;

FIG. 7 is a right side view thereof;

FIG. 8 is a top front right perspective view thereof;

FIG. 9 is a top plan view thereof;

FIG. 10 is a bottom plan view thereof;

FIG. 11 is a front view of the auxiliary monitor system design of FIG. 1 in an open pivoted configuration;

FIG. 12 is a right side view thereof;

FIG. 13 is a top front right perspective view thereof;

FIG. 14 is a top plan view thereof;

FIG. 15 is a bottom plan view thereof;

FIG. 16 is a right side view of the auxiliary monitor system design of FIG. 1 in an open pivoted display configuration;

FIG. 17 is a front view thereof;

FIG. 18 is a bottom plan view thereof;

FIG. 19 is a top plan view thereof;

FIG. 20 is a top front right perspective view thereof;

FIG. 21 is a top back right perspective view thereof; and,

FIG. 22 is a back view thereof.

The broken lines showing the laptop are included to illustrate environmental structure; the broken lines showing portions of the auxiliary monitor system are included to illustrate portions of the article; all broken lines form no part of the claimed design.

1 Claim, 22 Drawing Sheets
